CASH REGISTER

Leo G. A. Kömmling, Berlin, Germany, assignor
to the National Cash Register Company, Dayton, Ohio, a corporation of Maryland

Application October 27, 1933, Serial No. 695,413
In Germany November 5, 1932

5 Claims. (Cl. 101—3)

This invention relates to improvements in cash registers and like machines, and is particularly adapted to be used in connection with printing mechanisms on machines of the type shown and described in United States Letters Patent to B. M. Shipley No. 1,360,151, dated November 23, 1920.

The main purpose and object of this invention is to design a printing mechanism having novel means for embossing or printing upon a sales slip some record or identification to show that the slip was properly printed by the machine, which in turn insures that the amounts printed on the slips have been properly registered in the machine.

In the present invention this manner of marking or identifying the sales slips is accomplished in a novel manner and by novel mechanism which immediately after the machine is started grips the sales slip and holds it in position while the same is being printed, after which said mechanism is rendered operative to feed the slip out of the machine on a table so that it may be readily removed by the clerk, and either handed to the customer or placed with the bill of goods to be delivered.

Another and more specific object of this invention is to provide gripping and feeding means with suitable characters of any desired form, which characters will be impressed adjacent the edges of the sales slip as the same is being fed toward the table from which it is later removed by the clerk.

With these and incidental objects in view, the invention includes certain novel features of construction and combinations of parts, the essential elements of which are set forth in appended claims and a preferred form of embodiment of which is hereinafter described with reference to the drawing which accompanies and forms part of this specification.

40 Of said drawing:

Fig. 1 is a side elevation, partly in section, illustrating the novel mechanism for feeding and embossing the sales slip.

Fig. 2 is an edge elevation, partly in section, 45 of a portion of the mechanism shown in Fig. 1.

Fig. 3 is a fragmentary view, in reduced scale, of a sales slip, showing the location of the data printed thereon relative to the embossing adjacent the edges thereof.

50 *Detailed description*

The printing mechanism with which the present invention is adapted to be used includes three sets of type wheels 30, 31 and 32 (Fig. 2), the type 55 wheels 30 being the amount wheels, the wheels 31

the consecutive number wheels, and the wheels 32 the date wheels. Associated with the printing wheels is the usual inking ribbon 33 shown in dot and dash lines. Below the type wheels is arranged the usual guide or table 34 adapted to receive a sales slip 35, or any other material upon which it is desired to print, to receive the record of the sale as indicated in Fig. 3, which record includes the date, consecutive number of the sale, and the amount of the sale. A hammer 36 (Fig. 10 1) is arranged below the table 34 and adapted to be moved upwardly to contact the sales slip 35 with the type wheels to imprint the amount, consecutive number and date set up on the respective wheels. This hammer operates through an opening (not shown) in the table 34.

On each side of the groups of type wheels is a segment 37, each of which is held by a spring 38 against a stop pin 39. There is only one of the springs 38 and stop pins 39 shown.

Cooperating with the segment 37 is a pair of feeding segments 40 (Figs. 1 and 2) secured to a shaft 41 rotatably supported by two arms 42. These arms 42 pivot on a shaft 43 and are connected by springs 44 to arms 45 which are secured to the shaft 43. There is only one of the arms 45 and one of the springs 44 shown.

Also secured to this shaft 43 is an arm 44 carrying rollers 47 cooperating with a cam disk 48 fixed on a rotatable shaft 49. This shaft 49 is rotated one complete rotation by means not here shown during each operation of the machine.

The operation of the mechanism thus far described is as follows: It will be observed by the arrow shown in Fig. 1 that the shaft 49 rotates in a clockwise direction during which movement the cam 48 rocks the arm 46, shaft 43 and arms 45 in a counter-clockwise direction whereupon the springs 44 cause the arms 42 to be rocked likewise which lifts the shaft 41, thus causing the segments 40 to contact the segments 37. The table 34 is provided with slots 50 through which the segments 40 project.

The peripheries of the segments 37 and 40 are shown serrated in Fig. 1, and in Fig. 3 adjacent the edges of the sales slip 35 are shown two lines of short horizontal lines which represent embossing.

However, it is to be distinctly and clearly understood that in lieu of these lines the peripheries of the segments 37 and 40 may be engraved and embossed respectively with any suitable characters, words or hieroglyphics which may be desired by the proprietor. Whatever is placed on the peripheries of the segments 37 and 40 is

50 55

made to absolutely register, that is, where the characters are engraved on one pair of segments they are embossed on the other pair of segments so that the two pairs will always fit and properly line up when the segments 40 are raised into cooperative relation with the segments 37 so that when the sales slip is between the two, whatever characters or hieroglyphics are embossed or engraved on the two pairs of segments, will be embossed on the sales slip adjacent the edges thereof, as shown by the reference characters 51 in Fig. 3.

After the pair of segments 40 have been brought into cooperative relation with the segments 37, the segments 40 are rotated in a clockwise direction to feed the sales slip 35 toward the right as viewed in Fig. 1 to emboss along the adjacent edges thereof the characters on the peripheries of the segments 37 and 40 as the sales slip 35 is fed toward the right onto the inclined part of the table 34.

The mechanism for rocking the segments 40 after they have been lifted will now be described. Secured to the cam shaft 49 is a cam disk 55 operating with rollers 56 carried by a lever 57 pivoted on a stud 58 carried by one of the arms 45. The rollers 56 permit the shaft 43 to be rotated counter-clockwise by the cam 48 in the manner above described.

30 The lever 57 has a slot 58 through which extends a screw 59 which also extends through a slot 60 in an arm 61 integral with one of the feeding segments 40. The screw 59 is tightened or clamped in one of the slots in a definite fixed 35 position and allowed to slide in the other slot.

During the time the cam 48 is rocking the arm 45 counter-clockwise to raise the segments 40 into cooperative relation with the segments 37 the stud 58 is of course moved slightly toward the shaft 49, whereupon the rollers 56 will slide over the edges of the cam 55 and the screw 59 will slide in the slot 58 assuming that it has been clamped in a fixed position in the slot 60, which is the preferable way to secure these two parts together.

After the segments 40 and 37 have been thus engaged by the rocking of the shaft 43 the cam 55 through the lever 57 and screw 59 rocks the segments 40 in a clockwise direction while they are in engagement with the segments 37 with the sales slip 35 between them, thus feeding the sales slip toward the right and at the same time embossing characters represented by the lines 51 adjacent the edges of the sales slip. After this feeding and embossing has taken place the cam 48 rocks the arm 46 and shaft 43 clockwise to normal position whereby the arms 42 are likewise rocked to lower the shaft 41 and disengage the segments 40 from the segments 37. Immediately upon this disengagement of the segments 40 from the segments 37 the springs 38, there being one attached to each of the segments 37 immediately rocks said segments 37 clockwise to their normal positions in contact with the studs 39 45 where they always occupy the same positions relatively to the segments 40 when the latter are in their home positions thereby always insuring correct registration of the characters on the peripheries of the segments 37 and 40 to properly emboss the sales slip 35.

70 While the form of mechanism herein shown and described is admirably adapted to fulfill the

objects primarily stated, it is to be understood that it is not intended to confine the invention to the one form of embodiment herein disclosed, for it is susceptible of embodiment in various forms all coming within the scope of the claims which follow.

5 What is claimed is:

1. In a machine of the class described, the combination of means for printing on record material; a pair of feeding and embossing members; a second pair of feeding and embossing members adapted to cooperate with the first pair of members but normally disengaged therefrom; means for engaging the second pair of members with the first pair of members; and means for rocking 15 the second pair of members to cause both pairs of members to simultaneously emboss and feed the record material.

2. In a machine of the class described, the combination of means for printing on record material; a pair of feeding and embossing members; a second pair of feeding and embossing members adapted to cooperate with the first pair of members but normally disengaged therefrom; means for engaging the second pair of members with the first pair of members; means for rocking the second pair of members to cause both pairs of members to simultaneously emboss and feed the record material; and means to restore said first pair of members to normal independently of said 30 second pair of members.

3. In a machine of the class described, the combination of means for printing on record material; a pair of feeding and embossing members; a second pair of feeding and embossing members 35 adapted to cooperate with the first pair of members but normally disengaged therefrom; rockable means for supporting said second pair of members; mechanism for operating said rockable means to engage the second pair of members with the first pair of members, said mechanism including a cam and a resilient member; camming means; and means carried by said mechanism and operated by said camming means for oscillating the second pair of members.

4. In a machine of the class described, the combination of mechanism for printing on record material; feeding and embossing means; feeding and embossing devices adapted to cooperate with said means but normally disengaged therefrom; rockable supporting means for said devices; mechanism including a cam, a plurality of arms, and a spring for operating said supporting means to engage said devices with said feeding and embossing means; a second cam; and means carried 50 by one of said arms and operated by said second cam for oscillating said devices.

5. In a machine of the class described, the combination of mechanism for printing on record material; feeding and embossing means; feeding and embossing devices adapted to cooperate with said means but normally disengaged therefrom; rockable supporting means for said devices; mechanism including a cam, a plurality of arms and a spring for operating said supporting means to engage said devices with said feeding and embossing means; a second cam; a lever carried by one of said arms and operated by said second cam; and means intermediate said devices and said lever for oscillating said devices upon operation of said lever.

70 LEO G. A. KÖMMLING.
